(57) CLAIM

The ornamental design for a fishing lure, as shown and described.

DESCRIPTION

A portion of the disclosure of this patent document contains material which is subject to copyright protection, copyright 2003 Bryan Misiurski. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of my design for a fishing lure, shown with a hook (in dotted outline), the hook is not part of the design.

FIG. 2 is a top view thereof.

FIG. 3 is a rear view thereof.

FIG. 4 is a right side view thereof.

FIG. 5 is a front view, shown without a hook being used.

FIG. 6 is a left side view thereof; and,

FIG. 7 is a bottom view thereof.

The broken line showing of environment in the drawings is for illustrative purposes only and forms no part of the claimed design.
